UNITED STATES PATENT OFFICE.

ALBIN STEINER, OF SONNEBERG, GERMANY, ASSIGNOR TO GEO. BORGFELDT & CO., A CORPORATION OF NEW JERSEY.

CRYING DOLL.

1,085,640.

Specification of Letters Patent. Patented Feb. 3, 1914.

Application filed April 4, 1913. Serial No. 758,765.

To all whom it may concern:

Be it known that I, ALBIN STEINER, residing at Sonneberg, S. M., Germany, have invented certain new and useful Improvements in Crying Dolls, of which the following is a full, clear, and exact description, such as will enable others skilled in the art to which it appertains to make and use the same.

10 This invention relates to crying dolls.

One of the objects thereof is to produce a doll figure which, after being deformed or distorted out of its normal shape, will automatically right itself with extreme slowness, at the same time emitting a long sustained cry.

Other objects will be in part obvious and in part pointed out hereinafter.

This invention accordingly consists in the features of construction, combinations of elements and arrangement of parts, which will be exemplified in the construction hereinafter set forth and the scope of the application of which will be indicated in the following claims.

In the accompanying drawings wherein is shown one of the various possible embodiments of my invention, Figure 1 is a partial section showing the interior of the figure in elevation. Fig. 2 is a cross section on line 2—2 of Fig. 1, showing the base with parts carried thereby, the spring being omitted. Fig. 3 is a cross section on line 3—3 of Fig. 2. Fig. 4 is a cross section on line 4—4 of 35 Fig. 3.

Similar reference characters refer to like parts throughout the drawings and specification.

It is common knowledge that heretofore 40 dolls and toys have been constructed, capable of producing a cry or whistle when squeezed. In some of these the sound producing element has been rendered effective by air passing therethrough when the toy 45 was compressed; while in others the cry has been produced by the influx of air, as the figure resumed its normal shape. In all such devices, however, the air has been permitted to pass freely through the sound producing element, thereby permitting the figure suddenly to overcome its physical deformation. In such devices the cry is sharp and short.

The present invention differs from such

devices, in that the sound producing element 55 is the sole means for the ingress of air to the interior of the figure; and the air passage therein is trapped or restricted, so that the admission of air takes place with great difficulty, tending to produce a vacuum 60 therein as the figure tries to resume its normal proportions. This prevents the spring or other expanding means from acting quickly, on which account, the movement is slow, and the sound produced by the incoming air is long sustained.

Referring to the drawings, the doll or figure is seen to comprise a disk-shaped base 1 and a smaller disk-shaped head supporting member 2, which disks constitute the 70 rigid members of a bellows structure. Securely attached to the peripheries of said disks, as with glue, and completely enveloping the space therebetween, is provided a covering 3 of flexible air-tight material, 75 such as rubberized or oiled cloth, which serves as the flexible member of the bellows aforesaid. A spiral spring 4 interposed between the disks 1 and 2 tends normally to extend the bellows or body to the full length 80 of the covering 3, the enveloped space being occupied by air admitted through a perforation 5 located in the base. Weights 6 secured to the upper surface of the base keep the figure in equilibrium in an upright position. Also secured to the said upper surface is a sound producing member 7, which is disposed in operative relation to the perforation 5. This member comprises an inverted trough 8, closed at one end as at 9, which 90 end and the sides of the trough are fastened in an air-tight manner to the disk. Completely filling the open end of said trough is a short tube 10 having a reed-pipe secured within and completely closing its inner end. 95 This reed-pipe comprises a substantially V-shaped member 11 closed at its free end, as at 12, and communicating freely with the interior of the tube 10; and a thin flexible tongue or reed 13 which completely covers 100 the open upper side of the V-shaped member, and is tightly secured thereto for a short distance beyond the end of said tube. This reed is adapted to vibrate and, in a well known manner, to produce a musical 105 tone when air passes beneath the same into the interior of the reed-pipe and tube 10.

A head 14 representing any character

which it is desired that the toy assume is secured in any suitable manner to the upper side of the disk 2; and a dress or other superficial covering 15 loosely envelops the whole device from the neck to the base, said covering being suitably attached to the figure at the points mentioned.

From the foregoing, the operation of the crying doll may be understood. By pressing downwardly upon the head, the spring 4 is compressed and the figure crushed in a vertical direction. The collapse of the bellows forces air through the reed-pipe, freely in the outgoing direction—and through the perforation 5. When the figure is released, the spring tends to extend itself to its full length but, as the incoming air is trapped by, and passes with difficulty, the vibratory reed 13, a partial vacuum is produced within the figure and the return of the figure to its normal proportions is retarded. As a result air is drawn through the reed-pipe for a considerable length of time and the tone thereby produced is long drawn out.

It is to be noted, that as the base is flat there is a tendency for the admission of air through the perforation 5 to be somewhat restricted by the surface upon which the toy rests. Advantage is taken of this fact, by properly proportioning the spring 4 and the weight of the head 14, to produce an intermittent crying effect. This results from the fact that as the figure rights itself it oscillates from side to side in an irregular manner; and tips the base slightly, first up on one side then on the other, wherefore air is admitted to the reed in varying quantities.

As many changes could be made in the above construction and many apparently widely different embodiments of this invention could be made without departing from the scope thereof, it is intended that all matter contained in the above description or shown in the accompanying drawings

shall be interpreted as illustrative and not in a limiting sense.

What I claim and desire to protect by Letters Patent of the United States is:—

1. In a toy device of the character described, in combination, a flexible air-tight body having one end completely closed, and a closure for the other end of said body provided with a perforation therethrough; a spring disposed between the said ends of said body tending normally to extend the same; and a reed pipe interposed between said perforation and the interior of said body, said reed pipe being formed to permit the air contained in said body to pass freely therefrom through said perforation without causing sound when said ends are pressed together, and to permit the air to pass back into said body in a restricted manner, causing a crying sound, and retarding the action of said spring in returning said body to its original proportions.

2. In a toy device of the character described, in combination, a pair of vertically spaced disks, one of which has a perforation therethrough; a flexible air-tight envelop connecting the said disks; a spring interposed between said disks; and a reed pipe disposed in operative relation to said perforation, said reed pipe being formed to permit the air contained in said envelop to pass freely therefrom through said perforation without causing sound when said ends are pressed together, and to permit the air to pass back into said body in a restricted manner, causing a crying sound, and retarding the action of said spring in returning said body to its original proportions.

In testimony whereof, I have affixed my signature in the presence of two witnesses.

ALBIN STEINER.
